UNITED STATES PATENT OFFICE.

HENRY L. DE ZENG, OF GENEVA, ASSIGNOR TO HIMSELF, ALBERT G. LUCAS, OF UTICA, AND WILLIAM D. BURRALL, OF WATERLOO, NEW YORK.

FASTENING FOR RAILWAY-RAILS.

SPECIFICATION forming part of Letters Patent No. 334,696, dated January 19, 1886.

Application filed April 27, 1885. Serial No. 163,523. (No model.)

To all whom it may concern:

Be it known that I, HENRY L. DE ZENG, of Geneva, in the county of Ontario and State of New York, have invented an Improvement in 5 Fastenings for Railway-Rails, of which the following is specification.

In Letters Patent Nos. 145,991 and 155,369, granted to me, ties of metal with clip-pieces for connecting the rails to the ties are shown. 10 My present invention relates to the features of improvement in the fastenings for connecting the rails to the ties, as hereinafter fully described and claimed.

In the drawings, Figure 1 is a longitudinal section of the cross-rail near one end, the rail being in section. Fig. 2 is a plan view, and Fig. 3 an end view, of the clip-piece for one side of the rail. Fig. 4 is a plan, and Fig. 5 an end view, of the clip made use of at the 20 opposite side of the flange; and Fig. 6 is a plan view in smaller scale of the cross-tie and rails fastened thereto.

The tie A is of metal, and may be of wrought-iron or of malleable cast-iron, preferably the 25 latter. The end portions of this cross-tie are sufficiently broad to take a bearing upon the earth or ballast of the road. The central portion of each tie is by preference made narrower, as shown in the plan view, Fig. 6, so 30 as to lessen the weight of the tie and increase the elasticity of the same near the middle portion. In the top plate of the cross-tie there are mortises, as shown at b c. These are of a size adapted to receive the clip-pieces next 35 described.

In my aforesaid patents the metal of the cross tie is bent up to form lips at the inner sides of the rail-flanges. These are sometimes liable to bend and break. The mortise b is 40 in the proper position for receiving the movable clip-piece D. The same is made with a hook, e, adapted to pass down through the mortise b and catch beneath the top plate of the tie, and it is also made with a plate, f, to 45 rest upon the surface of the tie-plate, and with a hook, g, the end of which is inclined to pass up over the flange of the rail H. These clip-pieces D are preferably made of malleable cast-iron, and when the hook of each clip- 50 piece is passed down through the mortise b

the clip is firmly sustained against lateral pressure, and the rail-flange is also held down when passed in beneath the hooked end g.

The clip-piece K is adapted to the opposite side of the rail-flange H. It is made with a hook g' to pass up over the rail-flange, and with flanges f' to rest upon the top of the tie-plate, and with a hook, e', to pass in beneath the tie plate; but to facilitate the placing of the parts together; the mortise c is longer 60 than the mortise b, in order that the body of the clip and the hook e' may be passed down vertically through this mortise after the rail has been laid in place, and then the clip is slipped along endwise to bring the hook e' 65 beneath the top plate of the tie and the hook g' over the flange of the rail. To secure this clip K in place, a wedge may be entered vertically between the clip and the metal of the cross-tie at the outer end of the slot c; but I 70 prefer to make use of a tapering screw, L, the threads of which fit indentations in the outer end of this clip K, so that said screw, when screwed down into place, as shown in Fig. 1, will press the clip K firmly toward the 75 rail and secure the flange thereof. It is preferable to make the tie-plate at the end of the mortise c of an increased thickness, as at i, to form a bearing for the tapering screw or wedge; but I prefer to introduce a gib, n, the 80 ends of which pass above and below the tie-plate A, and the face of this gib next the tapering screw L is recessed to correspond to the screw-threads. It will be understood that the tapering screw L can be revolved to tighten 85 up the parts should they become loose, and that the jar or vibration of the rail or tie will tend to shake down the screw farther into its opening and tighten the parts automatically. The tie-plates with the slots that receive the 90 clips may extend across from one rail to the other, or they may be separate plates secured to cross-ties.

I am aware that a metallic cross-tie and rail have been connected by clip-pieces passing 95 through mortises in the cross-tie and hooking over the base of the rail and secured in place by wedges.

I claim as my invention—

1. The combination, with the rail and tie. 100

plate having mortises therein, of the clip-piece D, having a hook, g, to pass over the flange of the rail, a hook, e, to pass through the mortise in the tie-plate and hook beneath the same, the flanges f, to rest upon the surface of the tie plate at each side of the hook g, a clip-piece, K, similar to the clip-piece D, and a wedge-acting device passing through the mortise between the clip-piece K and the metal of the tie-plate, substantially as set forth.

2. The combination, with the rail and tie-plate, of the clip K, having a hook, e', passed through a slot in the tie-plate flanges f', to rest upon the tie-plate, and a hook, g', to pass over the rail-flange, and a wedge-acting device in the mortise between the clip-piece K and the metal of the tie-plate, substantially as set forth.

3. The combination, with the rail and tie-plate having mortises through the same, of the clip-piece K, having a hook, e', passed through one of the mortises in the tie-plate, flanges f', to rest upon the top of the tie-plate, and a hook, g', to pass over the rail-flange, and 25 a tapering screw, L, introduced between the

movable clip-piece K and the metal of the tie-plate, to press the clip-piece K to its place and hold the rail, substantially as set forth.

4. The combination, with the tie-plate and rail, of a clip-piece, K, having a hook to pass below the tie-plate, and a hook to retain the flange of the rail, and screw-thread indentations at the outer end of the clip-piece, and a tapering screw introduced between the clip-piece and the tie-plate, substantially as set 30 forth.

5. The combination, with the tie-plate and rail, of the clip-piece D, having hooks e g and flanges f, the clip-piece K, having hooks e' g' and flanges f', and screw-thread indentations at the end, and the tapering screw L, introduced between the clip-piece K and the thickened recessed portion behind the screw, 40 substantially as set forth.

Signed by me this 4th day of April, A. D. 45 1885.

HENRY L. DE ZENG.
